UNITED STATES PATENT OFFICE.

SLOAN A. JONES, OF SPRINGVILLE, ALABAMA.

JOINT CLAMP.

Application filed February 6, 1928. Serial No. 252,210.

My invention relates to joint clamps for railroad rails and has for its object the provision of a device of the character designated which shall be simple of construction, easy of manufacture and which shall afford a combined clamping and supporting structure for the joint.

A further object of my invention is to provide an improved joint clamp for railroad rails which shall be particularly effective for supporting and clamping the joint on curved track and which shall embody a cooperating rail anchoring means.

A more specific object of my invention is to provide a joint clamp for railroad rails supported on spaced cross-ties and which shall embody a joint support and clamp combined with improved rail anchoring means whereby relative movement of the rail ends 20 is minimized and the rails are securely anchored against lateral displacement on the ties.

As is well known in the art to which my invention relates, the greatest difficulties in railroad track maintenance occur in the rail joints. Unless the rail ends at the joints are firmly held against relative movement, the ends of the joints may become battered by the passing of the locomotive and car wheels 25 thereover. Also, where relative displacement occurs and one rail end extends laterally beyond the other, the flanges of the wheels passing thereover are liable to catch on the protruding end and cause derailment. This 30 danger is especially existant on curved track on the outside rail of the curve where the pressure of the flanges against the sides of the rail is greatest. It is accordingly the prime object of my invention to provide 35 clamping means which shall embody a support and an anchor of such a character that the rails are supported and clamped against relative movement and the track at the joint is anchored against displacement to avoid 40 spreading.

I accomplish the above mentioned desired objects by providing an angle bar having a lower flange portion bent under the rail and extending beyond the base of the rail on the 45 opposite side. A cooperating angle bar is applied to the opposite side of the rail and has a lower flange extending beyond the base of the rail and resting upon the base member from the opposite angle bar. U bolts pass beneath the rail and connect the angle bars and base plate together and afford additional sup-

port for the joint, while the usual track bolts extend through the angle bars and rail to unite the joint. In addition to all this I provide a rail anchor cooperating with the first 60 mentioned angle bar and firmly secured to the ties. Connecting bolts extend through the upper end of the rail anchor, the angle bars and the rail to form a completely braced unitary structure.

A device embodying features of my invention is illustrated in the accompanying drawing forming a part of this application, wherein

Fig. 1 is a perspective view of a rail joint 70 embodying my invention;

Fig. 2 is a sectional view taken along the line II—II of Fig. 1, and

Fig. 3 is a sectional view taken along the line III—III of Fig. 1.

Referring now to the drawing for a better understanding of my invention, I show, in Fig. 1, a joint comprising meeting rails 10 and 11. As viewed in Fig. 1, the side of the joint in the foreground is the outer side of 80 the track with the pressure of the railway vehicle wheel flanges passing thereover acting in the direction of the arrow A. Hereafter in this specification, the side of the rails or joint in the foreground of Fig. 1 will be referred 85 to as the outside, and the opposite side will be referred to as the inside.

On the outside of the rails, at the joint, I provide an angle bar 12 having a lower flange portion 13 extending beyond the base 14 of 90 the rail and bent back, as shown, under the rail 10 to form a base plate 16 which extends entirely across beneath the rails beyond the base on the inside thereof. The rails 10 and 11 rest on spaced cross-ties 17 and 18 95 and the base plate 16 extends from tie to tie beneath the rail joint so as to form a support for the joint and prevent relative vertical movement between the rail ends.

On the inside of the rail I provide an angle 100 bar 21 having a lower flange portion 22, the lower flange portion being provided with an extension 23 which rests on the base plate member 16 of the angle iron 12. In order to provide additional support for the ends of the 105 rails I provide holes on opposite sides of the rails in the flanges of the angle bars at 24 and 26, Fig. 3, and connect the angle bars by means of U bolts 27 and 28 passing beneath the rails. The angle bars are connected to 110 the rails by the usual track bolts 29.

In order to support the joint against lat-

eral displacement on the ties 17 and 18 I provide rail anchors 31 and 32. The rail anchors 31 and 32 are made from rolled or pressed shapes to conform to the contour 5 of the angle iron 12 and are each provided with an outwardly extending foot 33 having holes for the insertion of spikes 34. The upper ends of the anchors are provided with holes 36 which come opposite holes 37 extending through both of the angle irons and 10 through the rail whereby they all may be connected and tightly bolted together by means of track bolts 38.

The angle irons and anchors employed in 15 my improved joint clamp are especially adapted for easy manufacture as they may be rolled out and pressed to shape and do not require special casting operations or cutting and wasting of material such as is the case 20 with joint clamping means with which I have heretofore been familiar. The angle iron 12 being disposed on the outside of the rail and having the base plate 16 integral therewith prevents relative lateral displacement of the 25 rail ends due to pressure on the inside and the U bolts 27 and 28 connecting the opposed angle bars beneath the joint, form a unitary supporting structure, simpler and stronger than any with which I have heretofore been 30 familiar. Furthermore, the rail anchors 31 and 32, bolted through the angle bars and rail and securely fastened to the ties, prevent lateral displacement of the joint as a whole and consequent spreading of the track.

35 From the foregoing, it will be apparent that I have devised an improved rail joint, simple of construction, easy of manufacture

and effective to provide a unitary joint structure wherein lateral displacement of the joint or its component parts is prevented.

40 While I have shown my invention in but one form, it will be obvious to those skilled in the art that it is not so limited, but is susceptible of various changes and modifications, without departing from the spirit 45 thereof, and I desire, therefore, that only such limitations shall be placed thereupon as are imposed by the prior art or as are specifically set forth in the appended claim.

50 What I claim is:

55 In a joint clamp for railroad rails resting on spaced cross-ties, an angle bar for the outside of the joint and having a flange bent under the joint to form a base plate extending from tie to tie and entirely across beneath the rail and beyond the opposite side thereof, an angle bar for the inside of the rail and having a flange with a base portion resting on the extended base plate portion of the opposite angle iron, U bolts extending across beneath the rails on opposite sides of the joint and connecting the flanges of the angle bars together, a rail anchor conforming in shape to the angle bar for the outside of the joint and bearing thereagainst from base to top thereof, said anchor having a horizontally extending portion provided with 60 holes for spiking to the tie, and securing bolts extending through the two angle bars, the rail and the rail anchor.

65 In testimony whereof I, SLOAN A. JONES, affix my signature.

70 SLOAN A. JONES.
